(57) **CLAIM**

The ornamental design for a can storage and dispensing container for a refrigerator, as shown and described.

DESCRIPTION

FIG. 1 is an upper left perspective view of a can and storage dispensing container for a refrigerator showing our new design, shown mounted on the door of a refrigerator;

FIG. 2 is an upper right perspective view of the can and storage dispensing container for a refrigerator;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines shown in the drawing disclosure are for illustrative purposes only and form no part of the claimed design.
